COMPARTMENTED FOOD WARMING INSERT FOR A SAUCEPAN OR THE LIKE

Richard B. Cronheim, 7 Upper Barnes,
St. Louis, Mo. 63124

Filed Feb. 12, 1968, Ser. No. 10,537

Term of patent 14 years

U.S. Cl. D44—1
Int. Cl. D7—02

FIG.1

FIG. 2

FIGURE 1 is a top plan view of a compartmented food warming insert for a saucepan or the like, showing my new design;

I claim:

The ornamental design for a compartmented food warming insert for a saucepan or the like, as shown.
